UNITED STATES PATENT OFFICE.

ANSON J. BENTLEY, OF NILES, OHIO.

FREEZING CAN.

Application filed April 14, 1922. Serial No. 552,747.

To all whom it may concern:

Be it known that I, ANSON J. BENTLEY, a citizen of the United States, and a resident of the city of Niles, in the county of Trumbull and State of Ohio, have invented an Improvement in Freezing Cans, of which the following is a specification.

The present invention relates to improvements in freezing cans used in the manufacture of ice and particularly to the type of can used in what is known as the raw water can system of ice making.

In this system it is customary to use freezing cans immersed in an appropriate freezing solution, such as brine, which is circulated around the cans. In order that the impurities commonly present in water available for the manufacture of ice may not be frozen into the finished cakes, a current of air is introduced at or near the bottom of the can. The agitation of the water caused by this air current is such that impurities are not frozen into the ice, but are collected in the small amount of water which remains unfrozen in a pocket in the ice cake at the termination of the freezing period.

It is an object of the invention to improve the construction of this type of can so that it may be economically manufactured and prove efficient and durable in use.

Some refrigeration engineers prefer to introduce the air into the water within the can at a comparatively low pressure while others prefer a higher pressure. In the so-called low pressure systems it is desirable to permit the air to escape into the water at a point near the middle of the bottom of the can while in the so-called high pressure systems the air may be permitted to escape into the water at a point in the walls of the can slightly above the bottom. It is to a can adapted to be used in the low pressure system that the invention is particularly directed.

There are several known means of forming an air conduit from a point adjacent the top of a freezing can to the proper point for the discharge of the air into the water, among them being the means disclosed in Patent No. 1,427,936 granted to me wherein an air conduit is formed between overlapping portions of the sheet metal constituting the walls of the can. For the purpose of illustrating and describing the present invention a preferred embodiment thereof in-

cluding the type of air conduit shown in the above mentioned application has been selected and shown in the accompanying drawings wherein,

Figure 1 is a perspective view of a freezing can embodying the invention. 60

Figure 2 is a plan view of the bottom of the can,

Figure 3 is a sectional view on the line 3—3 of Figure 2. 65

Figure 4 is a detail cross-section on the line 4—4 of Figure 2,

Figure 5 is a view of the underside of the can showing a modified construction.

Figure 6 is a section on the line 6—6 of Figure 5. 70

Figure 7 is a detail cross-section on the line 7—7 of Figure 5.

The general features of construction of the ice can may follow any approved practice but preferably the can is made in accordance with Letters Patent No. 1,027,802 granted to me on May 28, 1912. The four side walls of the can are formed from two properly shaped sheets of galvanized steel, 75 one sheet forming the side wall 1 and the end wall 2 and the other sheet forming side wall 3 and the end wall 4. A third piece of sheet metal is suitably cut and formed to constitute the bottom 5 of the can. A stiffening rib 6 may be embossed in the side walls of the can. 80

In order to form air conduit 7 the sheet 3 is grooved or corrugated along its edge where it overlaps the edge of the sheet 2 90 when the can is assembled. This forms, in cooperation with the sheet 2, an air conduit extending from the top of the can to the bottom of the side wall.

In order that an air conduit thus formed of the sheet metal of the can may be extended to a point near the center of the bottom of the can, a suitably formed member 8 provided with a groove 9 extending from one end thereof to a point adjacent the other end and provided with a hole 10 for the escape of air, may be suitably attached as by soldering or welding or both to the bottom of the can and an elbow 11 having one arm extending into the vertical conduit 7 and the other extending into the horizontal conduit 9 may be put in place as the bottom of the can is assembled with the sides in order to connect the vertical part of the conduit with the horizontal part. 100

This construction lends itself readily to the accepted practice of assembling cans of this type. For example, the two side wall members may be brought together and riveted at adjacent corners as indicated in Figure 1. A suitable number of rivets 12 may be used and a double row of rivets will be used on opposite sides of the conduit 7. These side or corner seams may then be soldered. The can bottom, having been suitably formed in accordance with my prior patent referred to, may then have the plate 8 attached thereto and the elbow 11 may be inserted in the conduit 9. When the bottom, thus formed, is brought into proper relation with the previously assembled side walls, the upstanding arm of the elbow 11 may be slipped into the conduit 7. The can may now be riveted around the bottom edges in the usual manner and a reinforcing band 13 may be placed around the top of the can and riveted in place.

It is customary to render the seams of the can fluid tight by soldering. The soldering operation upon the seams between the bottom and sides is usually carried on by dipping the can in solder so that a portion of the can will be immersed, the solder flowing through the riveted joint or being applied from the inside of the can. It will be observed that the operation of soldering the seam will also solder the elbow 11 tightly in each part of the conduit, that is, the vertical as well as the horizontal part. Furthermore, the elbow 11 will extend far enough into the two parts 7 and 9 of the conduit so that the solder will not flow over its ends and destroy the connection between conduits 7 and 9 through the elbow 11.

Figures 5, 6 and 7 show a slightly different embodiment of the invention wherein the conduit in the bottom of the can is formed by pressing a groove 14 upwardly into the same and affixing to the can in suitable manner as by soldering, welding or riveting, a plate 15 which, cooperating with the bottom of the can, forms a conduit to the center bottom of the can. A hole 16 is drilled or punched at the end of the groove 14 to permit the escape of air while a hole 17 is formed in the groove adjacent the point of attachment to the side wall so that the tubular elbow 11 may be inserted to connect the vertical and horizontal parts of the conduit. The soldering of the seams of the can may be effected in the same manner as previously described.

The above described construction provides a superior type of freezing can particularly suitable to the low pressure raw water system of ice making. It will be observed that there is no exposed tubing to be loosened by the action of the water in freezing or by the rough handling to which these cans are invariably subjected. The entire conduit is

as strong as the walls of the can and the two parts are securely and economically joined together by the tubular elbow 11.

It will be understood that the invention may be variously embodied and modified within the scope of the subjoined claims.

I claim as my invention:

1. A freezing can for use in the manufacture of ice having an air passage formed between overlapped wall members in one wall thereof extending vertically from the top to the bottom of the can and an air passage extending horizontally in the bottom of said can, the two passages being joined by a tubular member extending into each of said passages and having fluid tight connection therewith.

2. A freezing can for use in the manufacture of ice having an integral sheet metal air conduit formed between overlapped wall members extending from the top substantially to the bottom of the can and a tubular extension of said conduit to direct air from said conduit toward the center of the can, said tubular extension having one arm nesting in and forming a fluid tight joint with said vertical air conduit.

3. A freezing can for use in manufacturing ice comprising wall members and a bottom member, said wall members being overlapped and riveted along spaced parallel lines and separated between said lines to form an air conduit, the outer overlapped portion being riveted to the bottom to form therewith a fluid tight joint, a sheet metal strip secured to the inner face of the bottom member and forming between itself and said bottom member an air conduit extending to the center of the bottom, and a tubular elbow having its arms soldered respectively into the aforesaid air conduits.

4. A freezing can for use in the manufacture of ice comprising side wall members and a bottom riveted together having a two-part air conduit, each part being formed by spaced sheet metal members, the first part extending along an upright wall of said can between the wall members riveted together along two parallel lines and the second part being disposed in the bottom of said can between the bottom member and a strip secured thereto along two parallel lines and means connecting said two parts comprising tubular elbow having one arm connected to each part of said conduit by fluid tight joints, the outer sheet metal members of the conduits being riveted together to form a fluid tight joint between the bottom and side of the can.

5. A freezing can for use in the manufacture of ice provided with an air conduit extending vertically along a wall of the can from the top substantially to the bottom thereof formed integrally with the wall between overlapped wall members and a hori-

zontal extension of said air conduit comprising a sheet metal member formed with an embossed rib and assembled in overlapping relation with another sheet metal member in the bottom of the can and a tubular elbow having one arm soldered into the vertical part of said conduit and the other into the horizontal part to provide a fluid tight connection therebetween.

6. A freezing can for use in the manufacture of ice provided with an air conduit extending vertically along the wall of the can from the top substantially to the bottom thereof formed integrally with the wall between overlapped wall members and a horizontal extension of said air conduit comprising a sheet metal member formed with an embossed rib and laid upon and fastened to the bottom of the can, and means pro-

viding a fluid tight connection between the 20 vertical and horizontal parts of said conduit.

7. A freezing can for use in the manufacture of ice having a two part air conduit each part being formed by spaced sheet metal members, the first part extending 25 along an upright wall of said can and formed by overlapped wall portions at a joint therebetween and the second part being disposed in the bottom of said can and means connecting said two parts comprising 30 a tubular elbow having one arm connected to each part of said conduit by fluid tight joints.

In testimony whereof, I have signed my name to this specification this 11th day of 35 April, 1922.

ANSON J. BENTLEY.
